UNITED STATES PATENT OFFICE.

ARTHUR LITTLE, OF SWAMPSCOTT, MASSACHUSETTS.

DESIGN FOR A STOCK.

SPECIFICATION forming part of Design No. 31,021, dated June 13, 1899.

Application filed February 16, 1899. Serial No. 705,724. Term of patent 14 years.

To all whom it may concern:

Be it known that I, ARTHUR LITTLE, a citizen of the United States, residing at Swampscott, in the county of Essex and State of Massachusetts, have invented and produced a new and original Design for a Stock, of which the following is a specification, reference being had therein to the accompanying drawing, which is a plan view showing the collar portion of the stock flattened or straightened out and the tie portion thereof tied into a new style of bow-knot.

As shown in the drawing, the leading or material feature of my design consists in the bow-knot A, disposed and arranged as shown in the drawing, wherein the points a a extend upwardly toward the upper edge a' of the collar portion of the stock from the puffs a² a², which are at each side of the middle knot a³, each puff projecting above and be-

low knot a³. The rearwardly-extending portions a⁴ a⁴ of the tie each incline upwardly from the knot a³ to near the upper edge of the collar portion at the rear ends a⁵ a⁶ thereof. The collar portion presents above the tie a field a⁶, which is bounded by the upper edge a' of the collar portion and by the upper edges a⁷ of the rearwardly-extending tie portions a⁴ a⁴. The rearward extensions a⁴ a⁴ are fluted lengthwise at a⁸. 30

What I claim is—

The design for a stock as herein shown and described.

In testimony whereof I affix my signature in presence of two witnesses.

ARTHUR LITTLE.
